UNITED STATES PATENT OFFICE.

LOUIS JOHN BERGDOLL, NOW BY JUDICIAL CHANGE OF NAME LOUIS JOHN BERGSON,
OF PHILADELPHIA, PENNSYLVANIA.

PHONOGRAPHIC SOUND BOX.

1,423,387.

Specification of Letters Patent. Patented July 18, 1922.

Application filed December 11, 1916. Serial No. 136,218.

To all whom it may concern:

Be it known that I, LOUIS J. BERGDOLL, now by judicial change of name LOUIS JOHN BERGSON, a citizen of the United States, residing at Philadelphia, in the county of Philadelphia and State of Pennsylvania, have invented certain new and useful Improvements in Phonographic Sound Boxes, of which the following is a specification, reference being had therein to the accompanying drawing.

It is an object of this invention to provide a phonographic sound box, for use with the usual types of phonographic and other similar sound-reproducing machines, that from a record will reproduce music and other recorded sound most articulately and faithfully, and that will avoid to a minimum the production of sound occasioned by the usual scratch or contact interference of the stylus-point or equivalent part on the record.

With this object in view, the invention provides between the sound-box and stylus-point means so arranged as to absorb shocks imparted by inequalities in the record to the stylus-point in a plane substantially parallel with that of the diaphragm.

When read in connection with the description herein, the details of construction and arrangement of parts contemplated by the invention will be apparent from the accompanying drawing, forming part hereof, wherein an embodiment of the invention is disclosed, for purposes of illustration.

While the disclosures herein now are considered to exemplify a preferable embodiment of the invention, it is to be understood that it is not the intention to be limited necessarily thereto in interpretation of the claims, as changes and alterations within the limits of the claims can be made without departing from the nature and spirit of the invention.

Like reference-characters refer to corresponding parts in the views of the drawing, of which—

Figure 1 is a view in elevation;

Fig. 2 is a sectional view on the line X—Y, Fig. 1;

Fig. 3 is a view of parts as seen when looking in the direction of the arrow, Fig. 1.

Having more particular reference to the drawing, 4 designates a portion of a record-disk arranged to be rotated on a shaft 5 in

a manner common in the art, 6 designates a sound-box of usual form having a diaphragm 7 with which one end of a stylus-bar 8 is connected, and 9 is the sounder-outlet.

The other end of the stylus-bar is connected to the sound-box by a spring-controlled pivot-joint that includes a member 10 to which the stylus-bar is connected. This member is held against pivot-points 11 of the box by springs 12 extending laterally from the member and engaged by screws 13 that turn into extensions 14 of the box. The parts are disposed in a manner to permit the member 10 to rock under restraint of the springs 12 in a direction to permit the stylus-bar to vibrate in a plane substantially perpendicular to the diaphragm and thus impart reproductive vibrations to the diaphragm. Thus the axis of oscillation and vibration is substantially parallel with the plane of the diaphragm.

The member 10 has an arm 15 extending substantially at right angles therefrom on each side, and this arm carries pivot-points 16 against which a member 17 is held by springs 18. One of the springs 18 extends from each side of the member 17, and it is engaged in its free end portion by a screw 19 turned into the arm 10. The parts are disposed in a manner to permit the member 17 to rock on the pivot-points 16 under the restraint of the springs 18 in a direction to permit a socket 20 on the member carrying a stylus-needle or other record-engaging part 21 to vibrate in a plane substantially parallel to the plane of the diaphragm and in a plane substantially perpendicular to that of the record-disk. Accordingly, the axis of oscillation of the member carrying the record-engaging part is substantially parallel to the plane of vibration of the stylus-bar and substantially perpendicular to the diaphragm and the axis of oscillation of the member 10 and to the plane of vibration of the stylus-bar.

Inasmuch as all phonographic records, by reason of their composition and formation, are more or less rough in and along the groove in which the stylus-needle point or other record-engaging part travels, there is a tendency in the record to throw the stylus-point or the like up and away from the part of the groove in which it travels, this as a

result of the inertia of the stylus-needle or the like and its carrying-socket, and the point thereby is caused to miss or jump a considerable portion of the sound-undulations recorded upon the record. This is especially so in the case of the recorded finer or over tones.

The pivot-joint by which the socket is connected and that permits the needle or the like to vibrate in a plane substantially perpendicular to the record is provided to overcome this disadvantage. This action of the needle or equivalent part, however, is checked in one direction by one of the 15 springs 18 and in the opposite direction by the other spring 18, and the springs maintain the needle or the like in a normal position and effectually neutralize the inertia of the socket and the needle or other record-engaging part carried thereby. The result is that the record-engaging part rides snugly in the groove, as practically all mechanical reaction is eliminated, and the scratch that ordinarily results in extraneous 25 vibrations in the sound-box is minimized, since the point or the like no longer hops along the record-groove, but glides smoothly therein.

It is to be noted that this pivot-joint does 30 not permit flexure of the socket and record-engaging part carried thereby in any direction other than in a plane substantially perpendicular to the record-surface or substantially parallel with the plane of the diaphragm. Therefore, the pivot-joint by which the socket is connected in no way interferes with the action of the pivot-joint of the stylus-bar in permitting the transmission of all vibrations of the record-engaging 35 part to the diaphragm in a plane perpendicular thereto; but the socket pivot-joint eliminates or absorbs vibrations of the record-engaging part in the plane parallel to the plane of the diaphragm and thus it minimizes the transmission to the stylus-arm 40 and thus to the diaphragm of properties imparted to the record-engaging part by roughness or other conditions in the record not pertaining to the recorded sound.

50 Having thus described my invention,

what I claim as new, and desire to secure by Letters Patent, is—

1. In combination with a sound-box having a diaphragm and a stylus-bar connected therewith, a pivotally-mounted member connected with said bar arranged to impart vibration thereto in a plane substantially perpendicular to said diaphragm in response to properties in a record pertaining to recorded sound, a holder for a record-engaging part pivotally mounted on said member arranged to vibrate only in a plane substantially parallel with said diaphragm in response to other record properties, and a spring counteracting movement of said holder in both directions. 55

2. In combination with a sound-box having a diaphragm and a stylus-bar connected therewith, a spring-controlled pivotally-mounted member connected with said bar 60 and arranged to impart vibration thereto in a plane substantially perpendicular to said diaphragm, a holder for a record-engaging part rockable on said member on an axis substantially perpendicular to said diaphragm, and a spring restraining rocking movement of said holder in both directions. 65

3. In combination with a sound-box having a diaphragm and a stylus-bar connected at one end to said diaphragm, a spring-controlled flexibly-mounted stylus-bar holder connected to the other end of said stylus-bar and permitting vibration thereof in a plane substantially perpendicular to said diaphragm, a member flexibly mounted on 80 said stylus-bar holder to rock in a direction substantially parallel with said diaphragm, a spring restraining rocking movement of said member in both directions, and a holder for a record-engaging part on said 85 member. 90

In testimony whereof I affix my signature in presence of two witnesses.

LOUIS JOHN BERGDOLL.
Now by judicial change of name Louis John Bergson.
